ATTORNEY

UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

RADIATOR CAP.

Application filed September 28, 1926. Serial No. 138,145.

This invention relates to a cap for radiators, used in connection with internal combustion engines, and one of the objects of my invention is to provide a radiator cap which 5 can be used in connection with any style of radiator stem.

Another object of my invention is to provide a radiator cap that is not only highly ornamental, but one that can be quickly and 10 easily operated for the purpose of filling the radiator.

My invention will be readily understood after reading the following specification, 15 taken in connection with the annexed drawing, wherein:

Figure 1, is a part elevational and sectional view of the cap with one of the arms slightly removed from its normal position.

Figure 2, is a plan view of the cover of the 20 cap.

Figure 3, is a fragmentary view of the body portion of the cap, indicated by the arrow 3.

Figure 4 is an end view of the detached arm shown in Figure 1 looking in the direction of the arrow 4.

Figure 5 is a fragmentary view of a modified form of adapter shell, used in connection with the body of the cap.

Figure 6, is a fragmentary sectional view 30 of a modified form of attaching the arm to the cover and body.

In the drawing 1, is the body of the cap, the outer surface of which has thereon some 35 ornamentation 2. Preferably made integral with the body 1, is a set of ribs, arranged diametrically opposite. These ribs 5 and 6 are, in the form shown in Figures 1 and 3, spaced apart, thereby providing a channel 7 between them, the purpose of which will be 40 later pointed out. Fastened to the interior of the body 1, is an adapter shell 3, fitting against a shoulder 4, and removably held in place by any suitable means, as by set screw 8. The adapter 3, is threaded at 9, to fit on 45 the stem of a radiator.

On certain makes of radiators an internal 50 thread is required, on the cap, while on others an external thread is required, and when an internal thread is used on the radiator stem, then the adapter is made as shown in Figure 5. From the structure shown in 55 Figures 1 and 5, it will be apparent that the adapter 3, may have the threaded portion made to any given diameter, to fit any style of radiator stem so that the body portion of

my cap with the other associated parts which will be described, are universal for all caps, it being merely necessary to change the adapter to fit various styles of radiator stems.

A cover 10, is provided with two sets of 60 flanges 11 and 12, which are provided with a hole 13, for the purpose of pivotally anchoring arms 14 between the flanges 11 and 12. The arm 14 is preferably made highly ornamental in character and has a portion 15, 65 slightly narrower than the channel 7, so that the arm 14 may be turned downward positioning the portion 15 between and against the ribs 5 and 6. The lower part of the portion 15 is preferably enlarged as indicated 70 at 16 and is circular in form to fit a groove 17 in the lower end of the ribs 5 and 6, whereby the arm 14 may be pushed downward so that the part 16 snaps into the groove 17 and is held there under the resilient tension of the 75 gasket 18, which is preferably held in position in an annular groove in the cover 10. The ribs 5 and 6 are preferably provided with ornamental bosses 19, through which fastening means, such as rivets are passed which 80 also pass through the portion 15 of the arms 14 on the left side of Figure 1. This particular arm is therefore permanently fastened in position to the body 1, while the other arm 85 is adapted to be unlocked so the arm and cover 10 can be swung over to uncover the opening into the cap.

The top part of the cover 10 is preferably provided with a surface 20, and a hole 21, to receive a Boyce motometer or some other device or ornamental figure.

In Figure 6, I have indicated a modified form of holding the left hand arm or wing 14 in position. In this modification a portion 15 is provided with a shoulder part 22 which 95 fits a corresponding shoulder on one of the ribs and a screw 23 holds the arm in position.

From what has been said it will be clear that various changes may be made in the details without departing from the spirit of my 100 invention and the scope of the appended claims.

Having thus described my invention, what I claim is:

1. A radiator cap comprising, a body portion having means to fit a radiator stem, a cover for the body, and a gasket fitting between the cover and body, said body having exterior ribs diametrically disposed, each set of ribs being spaced apart to form a channel, 105 110

arms pivotally anchored to said cover and having portions fitting within said channels, means for permanently fastening one arm portion to its associated ribs and means for quickly detachably holding the other arm portion to its cooperating ribs.

2. A radiator cap comprising; a body portion having means to fit a radiator stem, a cover for the body and a gasket fitting between the cover and body, said body having exterior embossed ribs diametrically disposed, each set of ribs being symmetrically

arranged and spaced apart to form channels, ornamental arms pivotally anchored to said cover and having portions fitting within and against said channels, means passing through the embossed portions on one set of ribs and one arm portion to permanently hold its associated arm in place, at least one of said arm portions having a part to fit over the ends of its associated ribs to quickly detachably hold one of said arms in normal position.

In testimony whereof, I affix my signature.
EDWARD B. NOWOSIELSKI.
